DESIGN
BY CP & GB CORDON

Design for Spoon Handles
Patented 19 November 1850.

Charles P. Gordon & George B. Gordon of Boston Mass.
Letters Patent. No. 336. Dated Nov. 19. 1850.

The Schedule referred to in these Letters Patent and making part of the same.

To all Persons to whom these Presents shall come:

Be it Known
that we, Charles P. Gordon, and George B. Gordon, of Boston, in the County of Suffolk, and
State of Massachusetts, have invented or produced a new and useful ornamental design to be
wrought upon the handle of a spoon, fork, or such other article to which the same may be ap-
plicable; and we do hereby declare that the same is fully described and represented in the follow-
ing specification, and accompanying drawing, letter, figures, and references thereof.

Of the said drawing, Figure 1. denotes the design in ques-
tion, while Figure 2. denotes another design contemplated to be made or stamped upon the oppo-
site or back side of a handle of a spoon or other article, on whose front side our said new
or useful design is wrought in bas relief, either by stamping, rolling or carving the same thereon.

Our said design consists of a sprig or bead border a, a,
Figure 1. curved in an elliptical shape, and terminating in a leaf b, and one or more small-
er leaves c, c'. Within this border a, a, are two beads d, d. They spring from an ornament
e, at one end, and terminate at the other end in a grape leaf, and two bunches of grapes
as seen at f. From and about the above beads g, g' extends, as seen in Figure 1, and
terminate in a leaf ornament, as seen at h. The whole is to be cut in bas relief, or in reverse
thereof, as occasion may require.

What we claim as our invention, is the new and useful
ornamental design or configuration, substantially as represented in Figure 1, and as herein before described.

In testimony whereof we have hereto set our signatures, this twenty
fourth day of June A. D. 1850.
